FIG.1

FIG.2

FIG.3

FIG.4

FIG.5

FIG.7

FIG.6

FIG. 1 is a perspective view of a combined dispenser and closure cap for a pressurized can showing my new design wherein the dispensing nozzle is integral with the cover;

FIG. 2 is a top plan view thereof;

FIG. 3 is a side elevational view thereof;

FIG. 4 is a bottom plan view thereof;

FIG. 5 is an exploded, elevational view, partially broken away and partially in section, illustrating an alternative embodiment of my new design wherein the dispensing nozzle is separable from the cover;

FIG. 6 is a top plan view of the alternative embodiment; and

FIG. 7 is a fragmentary, bottom plan view of the alternative embodiment.

The side elevational view of FIG. 4 is the same as FIG. 3.

I claim:

The ornamental design for a combined dispenser and closure cap for a pressurized can, as shown and described.
